UNITED STATES PATENT OFFICE.

SYLVESTER EBERLY, OF MORENCI, MICHIGAN, ASSIGNOR OF ONE-HALF TO HOWARD S. MELLOTT, OF MORENCI, MICHIGAN.

BOTTLE-WASHING APPARATUS.

Application filed December 30, 1918. Serial No. 268,842.

To all whom it may concern:

Be it known that I, SYLVESTER EBERLY, a citizen of the United States of America, residing at Morenci, Lenawee County, 5 Michigan, have invented new and useful Bottle-Washing Apparatus, of which the following is a specification.

This invention relates to apparatus for treating articles.

10 This invention has utility when incorporated in bottle washers, especially power driven as to the washing operation.

Referring to the drawings:

Fig. 1 is a fragmentary plan view of an 15 embodiment of the invention in a washer for milk bottles, parts being broken away;

Fig. 2 is a partial longitudinal view of the washer of Fig. 1;

Fig. 3 is a transverse view, parts being 20 broken away; and

Fig. 4 is a detail view in perspective of the frame holding latch.

The reservoir 1 has thereover a main driving shaft 2 mounted in bearings 3, 4, 5. 25 The overhanging end of the shaft 2 carries fast driving pulley 6, and adjacent thereto idler pulley 7 loosely mounted on the shaft 2. A shifting of belt 8 from the loose pulley 7 to the fast pulley 6 effects the 30 power driving of the washer as herein disclosed.

Loosely mounted on the shaft 2 are collars 9 having radially extending bolts 10 with nuts 11 thereon for clamping frame members 12 into the desired radial position as to size of bottle being cleaned, in adapting 35 to the tank or reservoir 1. Spacers 13 from the bars or frame members 12 have bolts 14 therethrough for clamping outer frame members 15 in position parallel to the shaft 2 and member 12 of such frame.

In practice it is preferable to group the frames in lateral pairs primarily, with sets of four frames serving as a compact unit; 45 which sets of four frames or even sets of two frames may be adapted to any desired tank or reservoir extent for which the demands of the installation may require. As to the frames themselves, their extent may 50 be economically limited to the range for convenient reaching by the operator or attendant with a minimum of movement. The number of containers or bottles per frame may thus vary with size of bottle for 55 which the frame is designed. For instance,

with quart milk bottles, in the simplified form of the apparatus shown in Fig. 1, a frame may conveniently provide for the simultaneous washing of ten bottles.

Spaced along on the shaft 2 are bevel gears 16, which during driving actuation are in mesh with bevel pinions 17 on brush carriers or shafts 18 mounted against longitudinal movement by bearings 19, 20, at frame members 12, 15. The bearing 19 60 abutting the sleeve from the pulley 17 fast on the shaft 18, holds the shaft from movement outward or radially as to the shaft 2; while sleeve 21 abutting the outer side of the frame member 15 and fast with the shaft 70 18 keeps the shaft 18 from movement inward. A key 22, permits ready removal of the sleeve 21 from the shaft 18. A tack or nail 23 may serve to engage stem 24 of bottle carrier or brush 25 in mounting such 75 brush 25 for rotation with the brush carrier shaft 18.

Fast on shaft 2 is grooved collar 26 engaged by lever 27 having fulcrum bearing 28 in frame member 12. This lever 27 has 80 remote from the collar 26 a handle 29 with a relatively movable grip member 30 normally set by a spring 31 to engage notch 32 in frame member 15 when the pinions 17 are held in mesh with the gears 16. When it is 85 desired to shift the frame as a unit longitudinally of the shaft 2 to have the pinions 17 out of mesh with the respective gears 16, the handle 29 with its grip 30 is shifted to act as a latch holding in notch 33 of the 90 member 15, and the frame unit is locked out of driving relation as to the power rotation of the shafts 18. Under these circumstances a single frame, or desired pairs of frames may be used with no waste of power 95 in driving idle brushes. This is a matter of great simplicity and convenience for varying the capacity of the washer economically. The levers 27 accordingly serve for maintaining the frames in or out of position for 100 driving rotation of the brushes 25.

A simple mechanism is provided as a control means for shifting and for maintaining the frames in loading and washing positions. In a simple form for one-man operation upon one side of the tank 1, a pair of frames may be grouped for simultaneous 105 opposite travels.

On the medial transverse member 34 over the tank or reservoir 1, uprights 35 are 110

braced by connecting member 36. Each member 35 provides a fulcrum bearing 37 for rocking beam or bar 38 having terminal chain 39 extending to a frame, in this instance shown as to frame members 15. The bars 38 have offset free ends 40 providing fulcrum bearings 41 for levers 42, normally thrust upward by springs 43 to limit positions as determined by pins 44 in slots 45. 5

10 Riding over the offset portions 40 of the bars 38 are latches or locking bars 46 pivotally connected to the uprights 35 and provided with a notch 47 into which the upwardly thrust hand lever 42 may ride as a 15 frame ascends to position for bottles washed to be removed from the brushes 25 and bottles to be washed are charged thereon. When a frame is thus charged, bottles being removed in pairs and applied in pairs— 20 one in each hand of the operator, the operator pushes down on the projecting free end of the hand lever 42 for such frame, which lever 42 first moves as to the bar 38 to free the lever from the notch 47. Continued 25 downward movement, in the same direction as this release or unlatching movement, forces this newly charged frame downward into the reservoir, and simultaneously the adjacent connected frame with 30 washed bottles thereon is moved upward to locked position and the bottles with rotating brushes therein out of the water of the tank, the open ends slightly downwardly inclined for self draining. Furthermore, they 35 are in position just above guide apron or shield 48, which not only protects the operator from splashings, but guides the bottle up into position upon the brush 25 and holds it there during the submerged cleaning operation. 40

In forcing the bottles over the brushes 25, the neck of the bottle is inserted through guide ring 49 on stem 50 adjusted by nuts 51 in its locked mounting to frame member 45 15. These rigid guides accordingly serve to assist in maintaining the bottles in position during the mounting thereof on the brushes.

A steam line 52 may extend into the reservoir 1 to keep the temperature of the wash 50 water therein as desired. Overflow or discharge from the reservoir 1 may be past valve 53.

The operator who charges a frame with 55 bottles to be cleaned up to the capacity of such frame, in the single act of depressing lever 42 swings the newly charged frame into bottle submerging position. As the brushes 25 are being driven continuously, the washing proceeds without delay or any 60 other manual act upon the part of the operator. This continuous drive is by belt 8 on pulley 6, actuating gears 16 in mesh with the gears 17. This submerging of the frame with bottles to be washed, simultaneously 65 brings out of the bath the adjacent frame

full of washed bottles. The still rotating brushes therein supplement the draining of these bottles with slightly downwardly inclined open ends. The brushes 25 still rotate whether in or out of the tank or reservoir, or moving from one position to the other, due to the continuous drive from the pulley 6 through the gears 16, 17. Notwithstanding this rotation, the bottles do not spin off, as they might because above the 75 guide apron 48, for their weight holds them from such upward movement, but leaves them accessible for ready removal by the operator, for this frame is held in its up or locked position by the opposite lever 42 80 engaging notch 47 of the bar 46 as a companion bar to the bar just released. The capacity of the machine is up to the maximum speed of the operator, and with two operators, one for each pair of frames, such 85 operators may perform their duties entirely independently, for the dipping and lifting of the frames on one side of the shaft are entirely independent of the like operations on the opposite side. In fact, the opposite 90 pair of frames may be cut out from all driving, by a shifting of the hand levers 27, and driving on one side only thus occur. By pairing the frames, there is a normal balancing tendency therebetween, notwithstanding the driving for rotation independent of the shifting or travel actuation. Accordingly the act of frame releasing and pushing toward its central balancing position is 95 not arduous, and while under movement, the travel is easily continued past such balanced position to the fully submerged position which brings the opposite frame to locked out position and the frames are thus held. 100

When only inside brushes 25 are used, it 105 may be desirable to mount adjacent the guide ring 49, a spring leaf 54, as a means for offering some slight resistance in addition to the contour of the rotating brush for holding the bottles in position. 110

Again, in some instances of use it may be 115 convenient, if not absolutely required, that a brushing of the bottle outside occur in addition to the splashing and rotation as effected by the brushes 25. To provide for this, there may be mounted adjacent the pinion 17 to rotate therewith, a pinion 55 in mesh with pinion 56 on shaft 57 parallel with the shaft 18, and like the shaft 18, carried by the frame members 12, 15, which has bearings 58, 59, therefor. A sleeve 60, fixed by key 61 to the shaft 57 holds the shaft 57 from movement inward by abutting the frame member 15, while the bearing 58 abutting the sleeve of the pinion 56, precludes outward longitudinal movement of the shaft 57. A tack or nail 62 may mount for easy removal or replacement, a brush 63 configured to oppose the brush 25 for exterior scrubbing of a bottle mounted on the 120 125 130

brush 25, the bottle in position thereon having slow rotation so that the higher speed rotation of the brushes 25, 63, mounted on the brush carrier shafts 57, 18, effect a general rubbing of the entire outer bottle wall opposing the inner brush.

Oil cups 64, are provided for the bearings 3, 4, 5, of the shaft 2, and oil cups 65 for the bearings 19, 58. The pan 66 precludes oil drippings into the wash water of the reservoir 1. Grease cups 67 provide lubricant for bearings 20, 59. From pan supports 68 central downwardly directed stops 69 limit the downward dip of the frames by abutting the frame members 12, 15, so in limiting submergence from striking the bottles on the tank bottom, there is simultaneously a limit to the up-throw of the companion connected frame being withdrawn from the wash to position for bottle removal. This upper removal position, while with the inward end downwardly inclined sufficient for drainage, is not such a large angle from the horizontal as the submerged position, thus placing exterior bottle washing brushes well under the surface for avoidance of splashings.

What is claimed and it is desired to secure by Letters Patent is:

1. A reservoir, a driving shaft thereover, brush carrier frames swingably mounted on the shaft and movable into the reservoir, radially extending brush carriers approximating a common plane rotatably mounted in each frame, and means for rotating the carriers from the shaft independently of swinging the frames.

2. A reservoir, a bearing, a pair of relatively movable brush carrier frames anchored in alignment by said bearing to swing into the reservoir, brush carriers rotatably mounted in the frames, and con-

nctions between the frames swinging one thereof up as the other is swung down.

3. A reservoir, a bearing, a pair of relatively movable brush carrier frames anchored in alignment by said bearing to swing into the reservoir, brush carriers rotatably mounted in the frames, driving means for rotating the carriers, frame rocking means for effecting simultaneous opposite travel of the frames, and a latch for maintaining the frames in rocked position during carrier rotation.

4. A driving shaft, gears thereon, a frame mounted to swing about the axis of the shaft, gears mounted in the frame and in mesh with the gears on the shaft, brush carriers supported by the frame and connected to be rotated from said frame gears, and means for shifting the frame longitudinally of the shaft for throwing the frame gears out of mesh with the shaft gears to disconnect the carriers from actuation.

5. A driving shaft, gears thereon, a pair of relatively movable frames mounted to swing independently about the axis of the shaft, parallel brush carriers mounted in the frames and gears mounted in each frame, each in mesh with a gear on the shaft for rotating the carriers independently of frame swinging.

6. A bottle washer comprising a plurality of pairs of simultaneously oppositely rockable frames, bottle guides carried by the frames, rotatable brushes adjacent the bottle guides, a common driving shaft for the brushes, and means for shifting the frames as to the shaft for connecting and disconnecting the brushes of such shifted frame for actuation from the shaft.

In witness whereof I affix my signature.

SYLVESTER EBERLY.
